ABSTRACT

A motor-driven device for releasing the shutter, advancing the film and cocking the shutter of a camera, and permitting single frame or continuous exposures to be made. The motor control includes a single switch controlled by a relay coil. The relay coil is includable in and capable of being energized by either of two mutually exclusive circuit paths each including in series, one of the contacts of a two-position changeover switch which selects the particular path for energizing the coil. The motor controls a mechanical arrangement which has two sequences of operation; a first sequence which releases the shutter and places the changeover switch in the second position, and a second sequence which advances the film, cocks the shutter and places the changeover switch in the first position. An operating button is connected in series with the first circuit path and a transistor switch is connected in the second circuit path. A selector switch is connected between the two circuit paths. For single frame exposures the selector switch turns the transistor OFF when the button is depressed. For continuous exposures, the transistor remains ON all the time. A timing circuit is further added for time-delayed continuous exposures.

FIG. 2

FIG. 3

MOTOR-DRIVEN WINDING DEVICE FOR A CAMERA

This invention relates to a motor-driven film winding, shutter cocking and releasing equipment for a camera.

Conventional motor-driven winding, shutter control equipment is provided with a number of switches which control the motor directly and take into account the selection of single-frame operation, continuous operation and remote-controlled operation.

Since these numerous switches operate the motor directly, their size and capacity must be sufficient to permit the flow of motor drive current through the switches. This has caused accidents resulting from weak contacts of the switches and has been a drawback in the prior art devices both in maintenance and in the resulting size of the device.

An object of this invention is therefore to remove the above-mentioned defects.

A further object of this invention is to enable remote controlling with a simple circuit.

Another object of this invention is to provide circuit means without requiring a separate relay, such that during continuous phototaking the motor may be stopped for a fixed period of time during which the shutter and mirror may finish their operation thereby enabling the use of slow shutter speeds. An RC circuit is used for this purpose as a timing circuit, and it is comparatively more economical than the conventional relay.

The motor-driven winding and shutter release equipment of the camera of this invention is so constructed that a control switch is connected in the driving circuit of the motor, which is controlled by a relay coil. A changeover switch, alternately switched between two positions respectively, when the film winding is completed and when the shutter is released is provided. The changeover switch is in series with the relay coil. The relay coil is initially energized by depressing an operating button or remote control switch when the previous winding is completed, and the camera is ready for picture taking. This causes the motor to rotate so that the shutter is released, and the changeover switch is operated. A transistor is connected to the circuit changed over during single-frame phototaking, the connection between the base and the emitter of the transistor is short circuited by a blocking diode when the operating button or remote control switch is being depressed to make said transistor inoperative. The relay coil is deenergized and the motor stops running when the switch is changed over right after the shutter is released. When the said operating button or remote control switch is released, the transistor is made operative, the relay is reenergized again to rotate the motor, the film is wound and the shutter is cocked. The changeover switch is then returned to its other position which deenergizes the relay and the motor stops running. When making continuous photographs, the transistor is made to be in operating condition all the time by disconnecting the circuit which shorts the base and emitter of the transistor as the operating button or the remote control switch is depressed. The relay is therefore kept in operating condition during the entire period that the operating button or the remote control switch is depressed permitting continuous sequential operation of winding up of the film and shutter release wherein the motor is continuously running.

In order to perform continuous phototaking with a specified resting period following shutter release, the circuit which shorts the base and emitter of the transistor can include a timing circuit to keep the transistor in an operating state for a specified period following shutter release. The relay coil circuit will open during this time to stop the motor. After the specified period of time has passed, the timing circuit permits the transistor to operate and to energize the relay coil circuit thereby permitting the motor to perform film winding.

This invention will be described more in detail referring to illustrative embodiments shown in the drawing, in which:

FIG. 1 is a circuit diagram and a side view of a motor drive mechanism showing an embodiment of this invention in which the shutter has been released and the operating button has been freed during single phototaking;

FIG. 2 is a circuit diagram similar to that of FIG. 1 but wherein film winding has been completed and the motor is resting; and

FIG. 3 is a circuit diagram of another embodiment of this invention, including a timing circuit.

In FIG. 1, M is the motor, 1, 2, 3 and 4 are reduction gears in which the gear 4 is formed into one unit with the cam 5 which is provided with a protruding flange 5a. A spring 6 pushes the cam 5 leftward. A roller 7 is combined into one unit with the bevel gear shaft 8. The cam 5 is fitted on a shaft 8' with play therebetween and is constructed to move rightward. A bevel gear 8a is formed into one unit with the shaft 8 and engages with a large bevel gear 9. A coupling 10 which connects to the camera winding-up shaft is connected at the end of the gear 9. A release lever 11 and a release pin 12 which operates in the direction of the arrow serves to release the shutter. A return spring 13 returns the release pin 12.

One end of the release lever 11 is in contact with the protruding flange 5a. The lever 14 is free to rock by the movement of protruding flange 5a of the cam 5 and operates to change over switch S₂ between the a side and the b side through one end 17 of said lever. A return spring 15 is connected thereto. An operating button 17 which is usually open, closes a switch S₃ when depressed. S₁ is the switch of the relay coil Re which is in contact with the b' side when the coil is deenergized, thereby shorting the motor terminals. Tr is a silicon transistor. A bias resistor R serves to bias the transistor Tr. S₄ is a control switch for single-frame phototaking when in position S and for continuous phototaking when in position C. E is a power source. S₅ is a remote control switch in parallel with S₃. D₁ and D₂ are diodes which suppress the arc of the motor M and the relay Re, respectively; D₃ is a blocking diode and is a germanium diode in the embodiment as shown.

The operation will be explained in the following in order of actuation. FIG. 1 shows the state of operation when the operating button 17 is freed after the shutter has been released and the switch S₃ is opened. The base current of the transistor Tr flows along the path including the battery E—bias resistor R—base b'' of the transistor—emitter e of the transistor—and back to battery E. Accordingly, the coil of the relay Re is energized with the current flowing along the path including the battery E—relay Re—b side of switch S₂—transistor Tr and back to battery E. The switch S₂ is therefore changed over to the a' side. The motor then runs since the current now flows through the path including the battery E—switch S₁—motor M—and back to the battery. The cam 5 will rotate in the direction of the arrow via the gears 1, 2, 3 and 4. The bevel gear 8a also turns together with the cam 5 and the roller 7 to rotate the bevel gear 9 which winds up the film and cocks the shutter by way of the coupling 10.

When the film winding is completed, rotation of the coupling 10 stops because there exists on the camera side a limit to winding operation. Further rotation of the motor causes the cam 5 to move rightward along the roller 7, compressing the spring 6. By this movement, the lever 14 rotates clockwise and changes over the switch S₂ to the a side by means of end 16 of the lever 14. As a result, the coil of the relay Re is deenergized, the contact of the relay S₁ returns to the b' side and the motor M stops running. The motor makes a sudden stop because the contact with the b' side works as a brake. The results of these changes during the operation are shown in the circuit of FIG. 2.

The operation of the diode D₃ will be described in the following. In FIG. 2, after the switch S₂ has been changed to position a there exists a path from the transistor base b'' to the emitter e of the circuit consisting of the battery E—relay Re—aside of switch S₂, and control switch S₄. If the diode D₃ did not exist, the relay coil would be energized even after the changeover switch S₂ was put into position a by the current flowing through the base to emitter of the transistor, and the motor would not stop. To prevent this, the diode D₃ is inserted in reverse bias to the current flow for purpose of blocking this current flow.

If in the state of FIG. 2, the operating button 17 is depressed to close the contact S_3 , the coil of the relay R_e is energized with current flowing through the path including battery E —relay R_e —a side of switch S_2 —switch S_3 —and back to battery E . The contact S is changed over to the a side, and the motor M starts rotation. When the V section of the cam 5 comes to face the roller 7, the cam 5 is shifted leftward by the spring 6 and operates the release lever 11 and the pin 12 by the flange section $5a$ which releases the shutter of the camera. At the same time, since the flange section $5a$ rotates the lever 14, the switch S_2 is changed over to the b side by the end 16 of the lever 14.

By depressing the switch S_3 , the circuit including battery E —bias resistor R —diode D_3 —contact S_3 —and back to battery E is now connected in a series path. The base to emitter potential of the transistor Tr is therefore only the potential equal to the voltage drop of diode D_3 which, when a germanium diode is used as the diode D_3 , is about 0.2. Since this potential is insufficient to operate the silicon transistor Tr , the transistor stays in an OFF state as long as S_3 is depressed and accordingly, when S_2 is switched to position b the relay R_e is deenergized and the motor M stops running. When the operating button 17 is freed, the circuit including the battery E —bias resistor R —diode D_3 —switch S_3 —and back to battery E , is now opened and the transistor Tr is brought into operating state. The relay R_e then operates again and the above-mentioned sequence repeats, causing the film to wind up and the motor stops after completion of winding.

When the control switch S_4 is placed to the continuous phototaking side c , the transistor Tr is in an operating state regardless of the state of the switch S_3 . The relay coil R_e will always be energized either through the circuit including battery E —relay R_e —a side of switch S_2 —switch S_3 and back to battery E , when switch S_2 is in the a position, or through the circuit including relay R_e — b side of switch S_2 —transistor Tr and battery E when switch S_2 is in the b position. In other words, the motor M continues running and performs continuous phototaking by repeating the phototaking and winding sequences. When the operating button 17 is freed and the switch S_3 is opened the motor stops running after completing the last film winding.

This procedure is followed in the same manner when the remote control switch S_5 is inserted in parallel with the operating button 17 and the switch S_3 .

Another embodiment will be explained referring to FIG. 3, in which the interval of continuous phototaking is made variable. The speed of continuous phototaking must be determined depending on the purpose of the picture taking, the kind of shutter used, and, in the case of single-lens reflex camera, whether the mirror is raised up or not. In order to carry out continuous phototaking effectively, it is desirable to make the film winding speed as high as possible and to vary the interval between the shutter release and the initiation of the next winding depending upon the shutter used, purpose of photographing, etc. In FIG. 3, single-frame phototaking is shown by positioning switch S_4 into position S and high-speed continuous phototaking by positioning into position CH . The general procedure for varying interval phototaking is quite the same as explained referring to FIG. 1 and 2, and no explanation of the general operation will be given here.

In FIG. 3 Tr_2 is a transistor, C is a capacitor, R_v is a variable resistor and R_2 is a small resistor. A switch S_6 is ganged to the switch S_2 and functions to open at time of shutter release when S_2 is placed in its b position and close at completion of the film winding when S_2 is placed in position a . As shown in FIG. 3, the operating button 17 is depressed to close S_3 and the control switch S_4 is in the CL position. When the film-winding operation has been finished as hereinbefore described, the switch S_2 is in the a position and the relay coil is energized through the circuit including the battery E , relay R_e , a side of switch S_2 , switch S_3 , and back to battery E . The switch S is placed into the a position, and the motor M starts to rotate to release the shutter. Simultaneously with releasing, the switch S_2 is changed over to the b side.

At the same time the switch S_6 is also opened. In transistor Tr_2 , the base current path including flows through the circuit—battery E —variable resistor R_v —capacitor C —base of transistor Tr_2 —emitter of transistor Tr_2 —battery E . As a result, the base potential of the transistor Tr_1 becomes equal to the emitter potential of Tr_2 with current flowing through the path of the battery E , bias resistor R_1 , switch S_4 in position CL , transistor Tr_2 and back to battery E .

Therefore the transistor Tr_1 becomes nonconductive whereby, the relay coil R_e becomes inoperative, and the motor M stops.

After a certain period of time, which is determined by the time constant of the variable resistor and the capacitor, has elapsed, the base current of the transistor Tr_2 is reduced and consequently the voltage drop of the bias resistor R_1 is also reduced. The transistor Tr_1 then becomes conductive whereby the relay R_e operates again to rotate the motor M and wind up the film. Since the switch S_2 is changed over to the a position when the winding is completed, if the operating button 17 is kept depressed, the relay R_e is reenergized to release the shutter. At the time the film winding is completed and the switch S_2 is changed over, the switch S_6 is also closed simultaneously. This discharges the charge accumulated in the capacitor C through the circuit including capacitor C —small resistor R_2 —switch S_6 —and back to capacitor C —to prepare for the succeeding release. The resting period can be made as desired by selecting the capacitor C and variable resistor R_v properly. Since the resting period is reduced by reducing the resistance of variable resistor R_v , it is possible to vary the interval of continuous phototaking by adjusting the variable resistor R_v .

When the switch S_4 is set to the CH position or the S position, the timing circuit, i.e., the circuit consisting of the transistor Tr_2 —capacitor C —variable resistor R_v —small resistor R_2 and—the switch S_6 , has nothing to do with the operation, and the operation becomes the same as that shown in FIGS. 1 and 2.

Instead of the timing circuit as shown in FIG. 3, such circuits as the Schmidt trigger or a differential circuit could also be used. The remote control switch S_5 has the same performance as the operating push button switch S_3 .

As has been described, according to this invention, the driving current of the motor is directly controlled only by the switch contact of the relay. Chances for fault are therefore diminished and the maintenance is made easy. Moreover, not only the changeover from single-frame phototaking to continuous phototaking or vice versa is easily carried out, but also the same relay that controls the motor can be used when remote controlling and there is no need for a special relay for remote controlling. This serves to reduce the cost and since remote control is made possible by only connecting a simple remote control is made possible by only connecting a simple ON-OFF switch, the invented equipment can be conveniently used.

Furthermore, the invented equipment is advantageous both in space reduction and in cost economy, since the continuous phototaking that has a temporary resting period at releasing time needs only the connection of a simple timing circuit and can dispense with the use of a special output relay.

What is claimed is:

1. A drive device for a camera for releasing the shutter, advancing the film and cocking the shutter, capable of releasing and continuous exposure, and comprising,
  - a power source;
  - an electric motor;
  - a single switch for interconnecting said motor with said source;
  - a relay coil for controlling said single switch;
  - a changeover switch having first and second contact positions;
  - first and second circuit paths both including said relay coil in series therin and both mutually exclusively capable of energizing said coil from said source, said first and second paths including respectively said first and second contact positions in series therin;

driving mechanism means coupled to said motor and including means for producing a first sequence of operations when said coil is energized through said first circuit path, including releasing the shutter and placing said changeover switch in said second position, and further including means for producing a second sequence of operations when said second path energizes said coil, including advancing the film, cocking the shutter and placing said switch in said first position; an operating switch connected in series with said first circuit path; transistor switch means connected in said second circuit path, control means connected between said first and second circuit paths for keeping said transistor in an ON state during continuous exposure operations and keeping said transistor in an OFF state when said operating button is depressed during single-frame exposure operation, and a selector switch for selectively connecting said control means into said second path.

2. A device as in claim 1 wherein said transistor switch means has its emitter and collector connected in series with said relay coil through said second contact position of said changeover switch, and its base connected to one end of said power source, said power source connected in parallel across said last-mentioned series connection, said selector switch, said control means and said operating button connected in series between said base and the other end of said power source, whereby when both said selector switch and said operating button are closed, said emitter-base voltage is approximately identical and said transistor is in an OFF state.

3. A device as in claim 2 wherein said control means includes a diode connected in series with said selector switch and said operating button and biased to prevent base to emitter current flow when said changeover switch is in said

first position.

4. A device as in claim 1 wherein said first circuit path includes in series said power source, said relay coil, said first contact position of said changeover switch and said operating button.

5. A device as in claim 2 wherein said second circuit path includes in series said power source, said relay coil, said transistor means, and said second contact position of said changeover switch.

10 6. A device as in claim 1 and further comprising a remote control switch detachably connected in parallel arrangement with said operating button.

7. A device as in claim 1 and further comprising a timed delay circuit switchably connected between said transistor 15 means and said power source.

8. A device as in claim 7, wherein said timed delay circuit includes a further transistor having its collector connected to said selector switch and a capacitor and variable resistor connected between its base and one side of said power source, the 20 other side of said power source connected to its emitter.

9. A device as in claim 8 wherein said timed delay circuit further includes additional resistor means in series with additional switch means connected in parallel across said capacitor and wherein said additional switch means is ganged to said 25 change over switch.

10 A device as in claim 7 wherein said selector switch is a three-positioned manually movable contact switch, said selector being connected to said operating button for its first contact position for single frame exposure, to said timed delay circuit for its second contact position for delaying the timing of continuous exposures, and is disconnected for its third position for normal continuous exposures.
